(57) **CLAIM**

The ornamental design for a sensor housing, as shown and described.

DESCRIPTION

FIG. 1 shows an upper front right perspective view of the sensor housing;

FIG. 2 shows a lower front right perspective view of the FIG. 1 embodiment;

FIG. 3 shows a front view of the FIG. 1 embodiment;

FIG. 4 shows a right side view of the FIG. 1 embodiment;

FIG. 5 shows a left side view of the FIG. 1 embodiment;

FIG. 6 shows a rear view of the FIG. 1 embodiment;

FIG. 7 shows a top view of the FIG. 1 embodiment; and,

FIG. 8 shows a bottom view of the FIG. 1 embodiment.

Features shown in dashed line form no part of the claimed invention.
